UNITED STATES PATENT OFFICE.

NATHANIEL H. BENTON AND HERBERT L. GODDING, OF MADISON, WISCONSIN.

SULKY-HARROW.

SPECIFICATION forming part of Letters Patent No. 365,962, dated July 5, 1887.

Application filed November 9, 1886. Serial No. 218,359. (No model.)

To all whom it may concern:

Be it known that we, NATHANIEL H. BENTON and HERBERT L. GODDING, citizens of the United States, residing at Madison, in the 5 county of Dane and State of Wisconsin, have invented certain new and useful Improvements in Sulky-Harrows; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Our invention relates to harrows, and has for its object the production of an efficient sulky-harrow, which shall be capable of ready and complete adjustment, and also of the best work possible in pulverizing the soil and getting it in readiness for the reception of crop-seed.

In carrying our invention into practice we provide a double harrow-frame pivoted together at the adjacent ends and suspended 25 from the axle of the sulky by means of straps or chains, which allow it entire freedom in its movements and permit it to be adjusted, as may be required, to rest lightly and shallow upon the ground, or to rest more heavily and 30 run deeper thereupon as it is progressed over it. The front edge is suspended by chains or straps attached to a cross-tree secured to the hounds of the sulky, and these chains or straps may or may not be adjustable. The suspension 35 of the forward edge is intended to prevent the said edge from plowing into the earth and catching under clods and other obstructions, while the adjustment as to height or pressure upon the ground is effected by a 40 separate set of chains or straps. The forward straps, therefore, need not be adjusted except to take up slack, if need be, occasioned by the elevation or depression of the harrow-frames.

The axle of the sulky is provided with a 45 frame extending both forward and back of the axle. To this frame the hounds are secured, and this frame may be removably secured to the axle, so that it can be taken off, together with the other parts of the harrow, and the 50 axle and wheels used for other purposes, if required. To the axle-frame in the rear of

the axle is attached the suspending and adjusting means for the harrow-frames. Brackets or standards bearing rollers or pulleys in their upper ends are secured upon the frame, 55 and a strap or chain attached to each harrow-frame passes over each of these pulleys, and is attached to a foot-lever, which is swung or pivoted at one end to the frame and is adjustable upon a hanging arm, so that by elevating 60 or lowering this rear end of the foot-lever the harrow-frames are sunk or raised. The foot-levers are provided with pins which enter holes in the hanging arms, and with springs which keep the levers and arms tight against 65 each other and prevent them from being accidentally separated. The pivoted adjoining ends of the harrow-frames are also provided with an adjusting strap or chain, which is secured at the upper end to a cam which is pivoted on a rack-head fastened to the frame, and is provided with a lever or handle by which it is operated to raise or lower the center of the frames. A pawl having connection with a bell-crank lever near the top of the cam lever 70 or arm serves to engage with the rack-head and hold the cam at any point of adjustment, and can be operated by the grasp of the hand when operating the cam lever or arm.

The driver's seat is secured upon the axle-frame by being set in a box under one portion and extended out over the rear cross-tree, where it is slotted and provided with a binding-screw, which, in connection with the box under the middle cross-tree, permits the seat to 80 be set farther in or out, to accommodate a boy or a man, or a man of any height. An arm suspended from the axle-frame passes through a guide or way in or upon the harrow-frame at each end of the device and prevents the frame or frames from working endwise into the wheels. These arms may be hinged to the frame upon the axle to permit 85 forward and backward movement of the harrow-frames in a line with the progression of 90 the machine over the ground, or the same end may be accomplished by having the arms rigid and making the guides or ways capable of swinging forward and backward. The harrow-teeth are secured to the pieces of the 95 frame or frames in boxes or plates secured upon the sides of the frame, or by means of a

hooked bolt, which clasps the tooth, and is provided with a nut by means of which the hook is tightened upon the tooth.

The accompanying drawings illustrate what we consider the best means for carrying our invention into practice.

Figure 1 is a rear elevation of the device. Fig. 2 is a plan view of the same. Fig. 3 is a plan view of the harrow-frames. Fig. 4 is a detail of the harrow-beam. Fig. 5 is a side elevation of the handle. Fig. 6 is a side elevation of the foot-lever and means for holding it at different heights. Figs. 7 and 8 are detail views of the manner of securing the harrow-teeth.

Similar letters of reference indicate corresponding parts in all the views where they occur.

A is the axle, and B B the wheels, of the sulky.

C C' are the harrow-frames, having their ends pivoted together, as shown at c^x. This double frame is suspended from the axle through the medium of a suitable axle-frame 25 and suspending straps or chains.

The axle-frame is composed of the end pieces, D D, and the transverse cross-trees d d' d² d³, one of which cross-tree, d', rests upon the axle and is secured thereto in such manner as 30 to be removable, if desired, so that the entire frame and attachments, together with the harrow-frames suspended beneath it, can be taken off and the axle and wheels used for any other purpose, if desired. The hounds D' D² are secured upon cross-trees d d', and support the tongue in the usual way. To the hounds D' D², at a suitable point in front of frame-piece d, is provided a shorter cross-tree, d^x, from which chains or straps e e are suspended down 35 to the front of the harrow-frames C C', to keep the front of these frames sufficiently elevated and taut to prevent it from being caught under clods and other obstructions and from plowing or digging into the earth. These 40 straps or chains e e may or may not be adjustable; but I prefer to provide them with some convenient means for being shortened or lengthened, which may consist simply of hooking them higher up or lower down upon the 45 hooks e^x e^x on the cross-tree d^x.

About mid-width of the harrow-frames chains E E are secured, which extend up over pulleys or wheels f f, held in brackets or standards either above the frame or, more preferably, by hangers below it, marked F F, on the cross-trees d² d³, and are attached to foot-levers G G, which are swung to the cross-tree d^x, and have pins or projections g g, which enter any of the holes in the series in the pendent arms 55 H H, which project down from cross-tree d^x. Springs g^x g^x are provided upon the foot-levers, which bear against the arms H H and hold the said arms and levers close together and prevent the disengagement of the pins g g from the openings or holes in the arms H H. A chain or strap, I, is secured to the pivot c^x be-

tween the frames and is carried up over a cam, J, which is pivoted to a rack-head, K, secured upon frame-piece d². The cam is provided with a handle or arm, j, which lies in reach 70 of the driver. Upon this handle j is provided a bell-crank lever, j^x, to which is secured the long pawl-arm k^x, which extends down through suitable guides and engages with the rack-head K to hold the cam at any point of adjustment. 75 The pawl is operated by the grasp of the hand of the driver when operating the cam. By turning the cam forward or backward the center of the frames C C' is elevated or lowered, which adjustment may take place in unison 80 with or independent of the adjustment by the foot-levers, and one foot-lever may be adjusted without change of the other, so that every portion or part of the harrow-frames is independently adjustable. The chains E E are attached 85 to the frames C C' nearer the wheel ends than the adjoining ends. Arms O O are secured to one of the framing-pieces and extend down and hold the harrow-frames from working endwise into the wheels, as shown in Fig. 1. 90 These arms are hinged to the frame-piece to give sufficient oscillation of the frames in a line with the draft or direction of progression over the ground to avoid rigidity and danger of fracture by reason of it. The arms or projections O' O' are preferably provided with short lengths of pipe or tubing, through which the arms O O pass. These pieces of tubing are marked O^x O^x.

P P, &c., are the harrow-teeth, which are 95 held on the harrow-frame pieces by means of boxes or plates p p and hooked bolts p' p', or by the hooks alone, the hooks p' of which surround the teeth and hold them against the frame-pieces. The bolt portions of these parts 100 p' p' pass through the frame-pieces and are screw-threaded to receive a nut by means of which the hooks are firmly clamped upon the sides of the frame-pieces, and when desired to remove the teeth the nuts can be slackened for 105 that purpose.

The driver's seat L is mounted on the stem or support L', which is run under frame-piece d² in a box, l, and over frame-piece d³, where it is provided with a slot, l', and binding-screw l^x, by means of which construction the seat can be made to ride farther back or farther forward to accommodate the height of the driver, so that his feet can rest upon the foot-levers G G and be operated thereby.

The chains E E and I may be in the form of sprocket-chains, and the pulleys f f and face of cam J may be suitably formed to receive this form of chain.

Having thus described our invention, what we claim, and desire to secure by Letters Patent, is—

1. The combination, with the axle-frame and harrow-frame, of the suspending-chains E E, pulleys f f, over which said chains pass, 115 the foot-levers G G, to which one end of said chains are secured, the pendent arms H H,

having openings or holes, as described, for the reception of pins on the foot-levers, and springs upon the foot-levers to preserve the engagement between said pins and arms, substantially as set forth.

2. The combination, with the axle-frame and pivoted harrow-frame, of the chain or strap I, secured to the pivot of said frames, the cam J, having lever j, and means, substantially as described, for fixing the cam at any desired point of adjustment, and the chains E for independently adjusting the ends, the foot-levers G G, for operating said chains, having a pin or pins upon their sides and confining springs g^x, and the pendent arms H H, perforated as described, as set forth.

3. The combination, with the axle-frame having the downward-projecting pivoted arms O, of the swinging harrow frame or frames having the rigid arms O', extending upward 20 and provided with sleeves or pieces of tubing O^x O^x, through which the pivoted arms O project.

In testimony whereof we affix our signatures in presence of two witnesses.

NATHANIEL H. BENTON.
HERBERT L. GODDING.
